UNITED STATES PATENT OFFICE.

JACOB GESSERT, OF ROCHESTER, NEW YORK.

DRILL-BRACE.

No. 924,901.

Specification of Letters Patent.

Patented June 15, 1909.

Application filed October 24, 1907. Serial No. 398,944.

To all whom it may concern:

Be it known that I, JACOB GESSERT, of Rochester, in the county of Monroe and State of New York, have invented a new and 5 useful Improvement in Drill-Braces, which improvement is fully set forth in the following specification and shown in the accompanying drawings.

My present invention is a drill-brace or 10 ratchet drill designed more particularly for conveniently boring holes into or through metal plates or similar bodies near to other objects or parts and of difficult access, or where the room or space in which the brace 15 is used is small and contracted.

This invention is in the nature of a continuation of, or improvement upon, the invention shown and set forth in Letters Patent No. 812,198, issued to me February 13th, 20 1906, and it embodies new features and important improvements upon the said patented invention.

One object among others of my present invention is to provide means for determining 25 approximately the depth to which the drill shall advance in boring a hole in any given case, and so arranging the coacting parts that when a hole is bored to the prearranged depth the feed motion will automatically reverse and so operate to draw the drill out of 30 the hole bored by a continued action of the operating handle and without any inconvenient or troublesome manipulation of the parts being necessary.

Other novel features of this invention, and 35 the advantages resulting from their employment, will be brought out and made to appear in the following description, and the details of the improved construction particularly pointed out in the appended claims, 40 reference being had to the accompanying drawings which, with the reference numerals marked thereon, form a part of this specification.

Figure 1 is a side elevation of the drill-brace with a part of the sleeve broken away and longitudinally sectioned, the sleeve being shown in various positions by full and by dotted lines. Fig. 2 is a plan of the head of 45 the brace and associated parts seen as indicated by arrow *a* in Fig. 1, parts being broken away and horizontally sectioned. Fig. 3 is a plan of the drum and associated parts, the horizontal section being on the 50 broken dotted line *c c* in Fig. 1. Fig. 4 is a central longitudinal section of the head of the

brace and associated parts taken on the dotted line *b* in Fig. 2. Fig. 5 is an elevation of the head of the brace seen as indicated by arrow *d* in Fig. 1, the handle and the thimble 60 being transversely sectioned as on the dotted line at the point of the arrow, parts being broken away. Fig. 6 is a vertical transverse section of the head and some associated parts taken on the dotted line *f* in Fig. 2. Fig. 7 65 is a horizontal longitudinal section of parts beneath the drum taken on the dotted line *e e* in Fig. 4, further showing the interior construction, parts being shown in two positions by full and by dotted lines. Fig. 8 is a side 70 elevation of the drum and associated parts seen as indicated by arrow *h* in Fig. 1, a part of the disk being broken out and parts shown in various positions by full and by dotted lines. Fig. 9 is a plan of the lower end of the 75 drum, a part being broken out and horizontally sectioned on the dotted line *g* in Fig. 8. Fig. 10 is a plan of the drill-stock detached. Fig. 11 is a view of the upper end 80 of the core piece holding the nut for the feed-screw. Fig. 12, drawn to a reduced scale, is a plan of the handle and some associated parts showing, by dotted lines, the manner in which the handle breaks for various uses, the thimbles being longitudinally sectioned. 85 Fig. 13 is a plan of the stop-mechanism for the advance of the drill, detached, parts being horizontally sectioned. Fig. 14 shows the cam disks detached. Fig. 15 is a face view of one of the cam disks or cams for controlling the twin pawls. Fig. 16 shows a simple modification in the construction of the pawls. Figs. 7 to 11 and 13 to 16 inclusive are drawn full size and the remaining figures except Fig. 12, are drawn five-sixth size. 90 95

Referring to the parts shown 1, Figs. 1, 2, 4, 5 and 6, is the head of the drill-brace and 2 the operating handle for turning the parts. The head 1 carries a hollow drum 3, Figs. 1, 3, 4, 5, 8 and 9, holding, among other parts, a hollow core piece 4, Figs. 4 and 11, having at its upper end a nut 5 for a feed-screw 6. The head 7 of the feed-screw occupies an opening central in the circular portion 8 of the head 1 and is held to place therein by a 100 pair of radially-disposed flat keys 9, Figs. 1 and 2, seated in oppositely disposed cavities in the part 8 and entering at their inner concave ends an annular groove 10, Figs. 4 and 8, in the head 7 of the screw, the core piece, 105 the nut and the feed-screw being coaxial with the drum. The head of the feed-screw 110

extends a short distance above the head 1 and is tapered to a point to bear against a convenient part 58 to hold the brace against the pressure upon the point of the drill when 5 operating the device. The core piece 4 is designed to revolve freely within the drum 3 but it is held against longitudinal movements therein by a pair of opposing horizontal flat keys 11, Figs. 1 and 9, similar to the 10 keys 9, occupying transverse openings 12, Fig. 8, in opposite sides of the drum. The inner ends of these keys 11 are concaved and project into an annular groove 13, Fig. 4, in the core piece 4.

15 The feed-screw 6 is provided with a circular disk 14 immediately beneath the head 7 and against the circular part 8 of the head 1, Figs. 1, 4, 5 and 8, rigid with the feed-screw, there being a pair of small rods 15, Figs. 3, 4 20 and 8, rigidly fixed to the disk 14 and projecting into vertical tubes or sleeves 16 occupying corresponding cylindrical chambers in the drum 3. The rods 15 are disposed equally on opposite sides of the screw 6 and 25 parallel therewith, as shown, being formed at their lower ends with heads, like pistons, to cross the spaces within the respective sleeves 16. These rods and the sleeves together constitute parallel duplex connectors 30 for the disk 14 and the drum 3, and serve, also, to prevent the disk and the feed-screw 6 having any relative rotative motion independent of the drum. The rods have longitudinal motion in the sleeves 16 and the latter have longitudinal motion in the drum, which renders these two-part connectors extendible, allowing the drum to move a considerable distance toward or away from the disk as the core piece 4 with the nut 5 is 40 turned one way or the other on the feed-screw 6, Fig. 8 showing by full and by dotted lines the drum and the disk differently spaced. The sides of the drum are formed with longitudinal slits 17, Figs. 4 and 8, to 45 receive short pins 18 in the sleeves which prevent the latter from being at any time drawn out of the drum, the upper ends of the sleeves being also closed to prevent the escape of the headed rods 15 therefrom.

50 The core piece 4 reaches below the drum 3, as appears in Fig. 4, having its lower end made square in cross section, as appears in Fig. 7, and carrying thereon a ratchet 19, Figs. 1, 4 and 7. The extreme end of the 55 core piece enters a rectangular recess 20, Figs. 4 and 10, in the upper end of a socket ring 21, Figs. 1, 4, 5 and 10, carrying a drill 22, the ring being secured to the core piece by simple fasteners 59. Thus constructed 60 and arranged it will be understood that the core piece and the drill socket must turn with the ratchet.

65 The operating handle 2 is formed with a flat tapered bifurcated head 23, Figs. 1, 3, 4, 5, 7 and 12, holding the ratchet 19 between

its parallel branches 24 these branches being formed with similar opposite circular openings 25, Fig. 12, receiving within them respectively the lower cylindrical portion of the core piece 4 and the upper cylindrical portion 26 of the socket ring or drill socket 21, as appears in Fig. 4. The core piece and the drill socket together constitute a bearing for the head 23 of the handle 2 around which they may turn reciprocally when in the act 75 of drilling a hole.

The handle 2 turns the ratchet 19 one way or the other by means of a pair of opposing dogs or pawls 27 28, Figs. 1, 4 and 7, held to turn in horizontal directions between the 80 jaws 24 24 of the head 23, on pivot pins 29, Figs. 3, 7 and 12. The pawls are actuated by an interposed spring 30 which tends normally to bring their operating points alternately into engagement with the ratchet 19 85 on opposite sides, as clearly appears in Fig. 7, the ends of the spring occupying recesses in the opposing faces of the pawls. The pawls are further controlled by a pair of oppositely acting cam disks 31 32, Figs. 1, 3, 5, 7, 12, 14 and 15, in positions to press the rear sides of the respective pawls, the inner or operating face of each disk being formed with a cavity 57 and a low or thin part 33 with incline 34 leading up to the high or 95 thick part 35 of the disk.

The disks occupy cavities at the sides of the head 23, as shown, being joined rigidly and to turn as a single piece by a connecting shaft 36 passing laterally through said head 100 and adapted to turn freely therein. The disks are relatively so placed that the cavities 57 are substantially but not exactly opposite, the positions being such that when either pawl occupies the cavity in the adjacent disk and engages the ratchet 19 the other pawl will be held by the thick part 35 of the opposite disk temporarily away from the ratchet and so out of action. As will be seen by viewing Fig. 14 the two inclines 34 110 of the disks are alternated or right and left, so that as either pawl is, on account of the turning of the disks, gliding down one incline into the cavity 57 and into action with the ratchet the other pawl will be moving up 115 the adjacent incline out of the cavity of its coacting disk and out of action with the ratchet. Thus one pawl, as 28, may be brought into action with the ratchet by the spring 30 while the opposite pawl 27 is held 120 by the disk 31 away in idleness against the action of said spring. By slightly turning the disks the positions of the pawls will be reversed the pawl 27 then coming into engagement with the ratchet and the pawl 28 125 becoming idle. By these means when the pawl 28 is engaging the ratchet, as appears by full lines in Fig. 7, a swaying of the handle 2 forward and back will cause the drill 22 to advance and bore a hole; but if the con- 130

trolling disks be shifted, as stated, the feed motion will reverse and the drill withdrawn from the hole. During these retreat motions of the parts the pointed head 7 of the feed-screw is held against the fixed object 58 by the left hand of the operator grasping the stem or holder 60, Figs. 1 and 3, this holder serving some of the purposes of the element "L" shown and described in the Letters

10 Patent above mentioned.

The head 23 of the operating handle 2 is provided with a hollow cylindrical post 37, Figs. 1, 3, 4, 5 and 12, extending upward into a similarly-shaped cavity in the head 1, and 15 provided with a slender axial spring 38. This spring is under compression, being confined by a screw-cap 39, Figs. 2 and 4, in the head 1, and acts to press the head and the handle normally away from each other and 20 to otherwise relatively control them. The head 1 is also formed with similar circular openings in which are placed a pair of hollow cylindrical piston bodies or spring-holders 40, Figs. 5 and 6, parallel with each other and 25 with the post 37, these piston bodies having weak or slender springs 41 mildly compressed by screw-caps 42, Figs. 2 and 6.

A connecting frame 43, Figs. 1, 2, 5 and 6, is provided, having its upwardly-extended 30 ends joined to the respective spring-holders 40 near their upper ends, by means of screws or pins 44, projecting through slits 61, Figs. 1 and 6, in the sides of the head 1 the lower ends of the frame being connected with the 35 respective disks 31 32 by means of pins 45, Figs. 1, 3, 5 and 7. On account of this construction as the handle 2 and associated parts move away from the head 1 by the feed motion the connecting frame 43 and the 40 spring-holders 40 will move with them, being mildly urged that way by the springs 41, these springs serving only to insure these motions for the frame.

To stop the feed for controlling the depths 45 of the hole bored in any given case a shiftable arrester 46, Figs. 1, 2, 4, 5 and 13, is employed on the head 1. This arrester is a simple bar pierced at the expanded middle by a headed bolt 47, having a clamping 50 thumb-nut 48 of any common form. The head of the bolt is held to traverse a vertical rectangular race 49, Figs. 4 and 5, in the head 1, with the body of the bolt projecting through a slit 50 in the head 1. The surface 55 of the head 1 traversed by the arrester is graduated by transverse marks 51, Fig. 5, spaced by inches or fractions thereof as may be convenient, by means of which the arrester may be set for depths of holes as desired. The arresting bar 46 is in position to 60 catch pins 52, Figs. 1, 2, 4, 5 and 6, of the spring-holders 40 projecting through slits 53 in the head 1, as said holders move with the handle 2 in a direction away from the head.

65 When in drilling a hole the spring-holders

thus move sufficiently to bring the pins 52 against the bar 46 their advance, with that of the connecting frame 43, will be stopped and a continued downward or onward feed of the parts will consequently cause the cam 70 disks 31 32 to turn in the head 23. This will serve to reverse the direction of the feed motion and so cause the drill to retreat and be readily removed from the hole drilled. And 75 these shifting of the parts and the reversing of the feed motion all take place while the handle 2 is continuously swung alternately forward and backward in the act of turning the drill.

Fig. 14 is drawn to show the relative positions of the two disks 31 and 32. The pawls 27 28 are represented by dotted rectangles one occupying the cavity 57 in the disk 32 and the other pressing the thick part 35 of the opposing disk 31 close to the cavity 85 57 therein and in position to quickly pass into said cavity and assume control of the ratchet 19, as the disks are turned by the connecting frame 43, as above described.

With this device I prefer to form the operating lever or handle 2 with two flexible joints 54 55, Figs. 1, 3 and 12, and provide a slidable sleeve 56, Figs. 1, 2, 3, 5 and 7, of such length as to cover either joint alone or both simultaneously, as represented by full-line and dotted-line positions in Fig. 1. In cases where there is sufficient room for swinging the handle 2 the sleeve is disposed to cover both joints 54 55, as shown by dotted lines toward the left, the handle then 100 acting as a single or one-part lever. If the space in which the brace is to be used is restricted in any given case the sleeve may be moved to the position shown by full lines covering only the joint 54, allowing the handle to break at the joint 55 as appears by dotted lines in Fig. 12. If, again, the space in which to work be very small the sleeve will be shifted to the right, to cover the joint 55, as appears by dotted lines in Fig. 1, allowing the handle to break at the joint 54, as 105 appears also by dotted lines in Fig. 12.

It may be desirable sometimes in constructing these devices to employ two short thimbles, 62 63, Fig. 12, for the handle 2 instead of one long thimble 56 these short thimbles being adapted to cover or uncover the adjacent joints 54 55 respectively or either one singly as may be found necessary in given cases, this simple change being comprised in the invention. I also sometimes prefer to form the pawls as shown in Fig. 16 each with a cylindrical ring or band 64 adapted to turn freely on a stud 65 projecting from the thick end of the pawl. These antifriction rings are in positions to receive the action of the respective disks 31 32 when turned to shift the pawls, as above stated, causing the coacting parts to move upon each other more freely and with less friction. 110 115 120 125 130

What I claim as my invention and desire to secure by Letters Patent is:—

1. In a drill brace, a feed screw, a drum coaxial with the feed screw, there being relative longitudinal movement between the screw and drum a core piece within the drum rotatably connected thereto but held against longitudinal movement and having a coaxial cavity occupied by the feed screw, a drill 10 socket constructed to turn with the core piece, a nut for the feed screw carried by the core piece to advance the tool, and means for causing said drum and feed screw to turn together.
  15. 2. In a drill-brace, a drum, a core piece rotatably connected to the drum but held against longitudinal movement, a feed-screw disposed axially within the drum, a disk above the drum rigid with the feed-screw, longitudinal connectors for the disk and drum, said drum and feed-screw turning together and relatively longitudinally movable, a nut on the feed-screw within the drum connected to the core piece, a tool socket connected to the core piece, and means for turning the nut.
  30. 3. In a drill-brace, a feed-screw and a drum coaxially disposed, a disk over the drum rigid with the feed-screw and aiding the holding of the feed-screw against rotation, a core piece rotatably connected to the drum but held against longitudinal movement, connectors for the disk and the drum each having a part rigid with the disk and 35 coaxing part slideable in the drum, said two parts telescoping with each other, said connectors serving to cause the drum and the feed-screw to turn together but admitting longitudinal motion one upon the other, a 40 nut for the feed-screw held within the drum and connected to the core piece, and means for turning the nut.
  45. 4. In a drill-brace a drum and a feed-screw coaxially disposed the drum constructed to hold the feed-screw from rotation, a core piece held revolvably within the drum and rotatably connected to the drum and having an axial cavity for the feed-screw, a
- nut for the feed-screw held by the core piece within the drum, means for turning the core 50 piece and for preventing longitudinal motion of the core piece within the drum.
5. A drill-brace having a drum and coaxial feed-screw turning as a single body, a hollow core piece in the drum rotatably connected to the drum but held against longitudinal movement for receiving the feed-screw, a nut in the core piece receiving said feed screw, a ratchet on the core piece beneath the drum, a socket ring on the core 55 piece beneath the ratchet and constructed to turn with the core piece, a hand-lever held to turn upon the core piece, and pawls carried by the lever to engage the ratchet.
6. In a drill brace mechanism, a head, a core piece rotatably connected therewith, said core piece being provided with a tool socket and feeding mechanism, a hand lever rotatably mounted on said core piece for turning the latter and operating the feeding 60 mechanism, and a spring-pressed post on said lever entering said head to cause the latter and the lever to turn together as one piece.
7. A drill-brace having a head and an operating handle connected to turn therewith coaxially, the handle being laterally movable toward and from the head, means tending to normally press the head and handle away from each other, a tool socket and 70 driving means therefor carried by the handle, a controlling member carried by the handle for controlling the tool socket driving means, slides carried in the head to move toward or from the handle, means for connecting said slides with said controlling member, and a shiftable arrester on the head for 75 said slides.
- In witness whereof, I have hereunto set my hand this 19th day of October, 1907, in 80 the presence of two subscribing witnesses.
- JACOB GESSERT.
